UNITED STATES PATENT OFFICE.

JOHN J. BEATY, OF LAKE CITY, MINNESOTA.

AUTOMATIC WEIGHER.

1,279,227.

Specification of Letters Patent. Patented Sept. 17, 1918.

Application filed February 21, 1918. Serial No. 218,531.

To all whom it may concern:

Be it known that I, JOHN J. BEATY, a citizen of the United States, residing at Lake City, in the county of Wabasha and 5 State of Minnesota, have invented certain new and useful Improvements in Automatic Weighers, of which the following is a specification.

The invention provides an appliance of 10 novel structure for use in connection with threshing machinery and milling mechanism for automatically weighing grain or like commodity, the same operating to deliver the material in given quantity after 15 being set without requiring any special care on the part of the operator or other person.

The invention consists of a tilting hopper or like part adapted to receive the grain from a suitable source of supply, oppositely disposed receptacles or containers for receiving the grain from the hopper, such receptacles being connected with the hopper so as to move in opposite directions, and a scale mechanism adapted to be set and automatically tripped by the receptacles in their movement.

One of the main features of the invention is the provision of an apparatus of the character stated which is simple in construction 30 embodying a minimum number of parts and effective and reliable in operation.

The drawing illustrates a preferred embodiment of the invention, however, it is to be understood that in adapting the same 35 to meet different conditions, various changes in the form, proportion, and minor details of construction may be resorted to without departing from the nature of the invention as claimed hereinafter.

40 In the drawings:

Figure 1 is an elevation of an automatic weighing device embodying the invention, parts being broken away.

Fig. 2 is a horizontal section on the line 45 2—2 of Fig. 1.

Corresponding and like parts are referred to in the following description and indicated in both of the views of the drawings by like reference characters.

50 The numeral 1 designates a spout which projects from the threshing machine, grain

bin, or other source of supply of the material to be delivered in measured quantity. A tilting hopper 2 is disposed so as to receive the grain or other commodity from the spout 1, and its bottom is oppositely inclined to a centrally disposed discharge 3. Similar or like receptacles or containers 4 are mounted to receive a rectilinear reciprocatory movement and are connected to opposite ends of the hopper 2 by means of links 5 which are pivotally connected at their ends to the respective parts. The bottom of each receptacle or container 4 is inclined inwardly and downwardly as indicated at 6 to a lateral discharge 7. When the receptacles 4 are at the limit of their upward movement, the discharge 7 is closed, and when at the limit of their downward movement, the discharge is fully opened as indicated most clearly in Fig. 1. A vertically disposed guide 8 is arranged between the opposed sides of the receptacles 4 and serves to give direction to the receptacles in their reciprocating movements and to close the discharge openings 7 thereof when the receptacles are at the limit of their upward movement and are receiving a supply of material from the hopper 2. Lateral displacement of the receptacles is prevented by means of plates 9 secured to opposite sides of the guide 8 and having their vertical edge portions projecting so as to overlap the outer sides of the receptacles as indicated most clearly in Fig. 2.

By having the receptacles 4 connected to opposite ends of the tilting hopper 2 at points equi-distant from the axis of such hopper, the receptacles have a like movement in opposite directions, *i. e.*, when one receptacle is moving upward, the other receptacle is traveling downward and vice versa. The receptacle at the limit of its upward travel is the one receiving the material to be weighed, and the receptacle at the limit of its downward movement is the one discharging the measured quantity of material contained therein. The axis of the hopper 2 is indicated at 10 and the discharge opening 3 of the hopper moves from one side to the other of a plane passing vertically through the axis 10, as indicated by

the full and dotted lines in Fig. 1. The hopper 2 tilts so as to bring its discharge opening 3 over the corresponding receptacle 4 at the limit of its upward movement so 5 as to discharge the material therein, and the position of the hopper 2 shifts as the receptacles 4 move.

The scale mechanism comprises a trip 11, a spring 12, and adjusting means 18-19 10 for varying the tension of the spring 12. The trip 11 consists of a member pivotally supported at 13 and adapted to swing to project one edge or the other in the path of a projecting part 14 of the receptacles 4. 15 The edges of the pivotal member 11 are of similar contour so as to offer like resistance to the movement of the receptacles and which is essential to secure accuracy of weighing. Each edge of the trip comprises an upper 20 straight portion 15 and a lower curved portion 16. The spring 15 is of the helical contractile type, and one end is connected to the trip 11 as indicated at 17, and its opposite end is adjustably connected to the 25 guide 8 whereby provision is had for varying the tension of the spring to cause the trip to offer a greater or less resistance in a movement of the receptacles whereby the quantity of material to be weighed at each 30 operation may be varied and determined. It is to be noted that the spring 12 may be adjustably connected at either end to the part to which the spring is attached, or that any well known means may be resorted to for 35 varying the tension of the spring in order to adapt the appliance for weighing varying quantities. For convenience, the means illustrated are preferred and consist of a longitudinally slotted plate 18 and fastening 40 means 19. The spring 12 is attached at its upper end to the plate 18 as indicated at 20. The fastening 19 preferably consists of an element mounted in the guide 8 and threaded to receive a winged nut. The plate 45 18 is suitably graduated to indicate pounds or other quantity and is adapted to cooperate with an indicator 21 provided on the guide 8. The projections 14 carried by the receptacles 4 may consist of studs or the 50 like which extend into the path of the trip 11 so as to engage the edges thereof.

The operation of the appliance may be briefly stated as follows:—The grain or other commodity to be measured is led to the 55 tilting hopper 2 by means of the spout 1. Assuming that the parts are in the position indicated by full lines in Fig. 1, the grain delivered from the spout 1 passes into the hopper 2 and is discharged there- 60 from into the uppermost receptacle 4. The projection 14 of this receptacle is in contact with the adjacent edge of the trip 11, the latter offering a resistance to the downward movement of the receptacle proportionate to 65 the tension of the spring 12. After the re-

ceptacle has received a quantity of material sufficient to overcome the resistance offered by the trip 11, the latter is caused to turn about its pivot 13, thereby admitting of the receptacle descending and at the same time 70 the opposite receptacle ascends to a position to receive a charge. As the trip 11 moves the lower end of the spring 12 moves from right to left and after passing a dead point, the spring 12 contracts slightly and effects 75 a quick movement of the trip thereby bringing its opposite edge in contact with the projection 14 of the ascending receptacle. As the descending receptacle clears the lower end of the guide 8, its discharge opening 80 9 is uncovered thereby discharging the grain or other material contained in the receptacle. In the meantime, the empty receptacle which has moved upward receives a charge of material, and when the amount 85 of the charge reaches a point to overcome the resistance of the trip, the operation just described is repeated. It will thus be understood that the action is automatic after the scale mechanism has been set so long as the 90 material is supplied to the tilting hopper 2 by means of the spout 1.

What I claim is:

1. A weighing appliance of the character specified, comprising two receptacles adapted 95 to reciprocate vertically in alternate opposite directions, the receptacle at its highest point receiving the material to be weighed, and the receptacle at its lowest point discharging the material previously supplied thereto in a predetermined amount, a trip pivoted medially between the receptacles, elements projecting from the receptacles and adapted to engage the trip and sustain the receptacles in elevated position until 100 they attain a given weight and descend and reverse the position of the trip, and a spring coacting with the trip to hold the latter in operative position to sustain the elevated receptacle until the weight thereof overcomes 105 the resistance of the spring.

2. A weighing appliance as set forth in claim 1 with the addition of means for varying the tension of the spring according to a predetermined scale.

3. A weighing appliance of the character specified, comprising a vertically disposed guide, receptacles upon opposite sides of the guide and having their bottoms inclined inwardly and downwardly, and having discharge openings in their inner sides adjacent the bottoms and adapted to be closed by the said guide, a hopper pivoted to the guide intermediate of its ends and adapted to alternately discharge into the receptacles, 120 means connecting the receptacles with opposite ends of the hopper, a trip pivoted to a side of the guide, elements projecting from the receptacles and adapted to alternately engage the edges of the trip and coat there- 125 130

with to sustain the receptacles in elevated position when receiving the material to be weighed, a spring coacting with the pivoted trip to sustain the receptacles in elevated 5 position while receiving the material to be weighed, and means for varying the tension of the spring according to a predetermined scale, whereby the amount of ma-

terial to be weighed at each operation may be varied.

In testimony whereof I affix my signature 10 in presence of two witnesses.

JOHN J. BEATY.
